UNITED STATES PATENT OFFICE

JÓRGEN JÓRGENSEN KRÜGER, OF COPENHAGEN, DENMARK.

DRYING APPARATUS.

1,247,284.

Specification of Letters Patent. Patented Nov. 20, 1917.

Application filed September 27, 1916. Serial No. 122,534.

To all whom it may concern:

Be it known that I, JÓRGEN JÓRGENSEN KRÜGER, a subject of the King of Denmark, residing at Copenhagen, in the Kingdom 5 of Denmark, have invented certain new and useful Improvements in Apparatus for Drying Organic Substances, of which the following is a specification.

This invention relates to apparatus for 10 drying organic substances, whether natural or manufactured. Hitherto such substances have commonly been subject to the formation of a hard rind or shell of dried material by the superficial action of the heat and evaporation on them; which rind or shell 15 prevents the proper action of the heat or drying agent on the internal portions of such material, so that the exterior of a joint of meat, for example, may be excessively 20 dried and hardened while the interior portions of the meat will remain incompletely dried or not dried at all. An equalized 25 drying operation resulting in the homogeneous condition of the substance treated is manifestly important; and the chief purpose 30 of this improvement is to insure such equality and homogeneity. To this end, I embed the substances to be dried in beds of pulverulent absorbent material, which will withdraw moisture from the superficial parts 35 of the substances treated but will also restore such moisture thereto when the drying threatens to become excessive and will thus constitute an automatic means of regulation, keeping the surfaces of the articles soft and consequently permitting the action 40 of heat and evaporation through these parts on the interior parts of said substances. I also support said beds separately in open 45 boxes in cars, permitting free access of heat and air to said beds and through the latter to said embedded substances. The details of said invention are hereinafter more particularly set forth, and the novelty of said invention is defined in the appended claims.

In the accompanying drawings:

Figure 1 represents a longitudinal vertical section through drying apparatus embodying my invention;

50 Fig. 2 represents a horizontal section through the same on a plane above the pipe 17 and ventilator 16 hereinafter described;

Fig. 3 represents a vertical cross-section through Fig. 1 taken at a point to the right of pipe 22, looking to the left;

55

Fig. 4 represents a longitudinal central detail view of one of the drying beds; and

Fig. 5 represents a similar view of a modified form of the same.

In said drawings, 1 designates an elongated receptacle or casing having one end adapted to be opened to receive cars 4, which are run into said receptacle on small wheels over rails 3 longitudinally fixed on the bottom plate of said casing. Said open 60 end of the receptacle, inclosure or casing, is closed at will by a removable cover 2.

These cars enter one after the other, are provided with open sides and, as herein-after explained, carry the drying boxes containing the articles or substances to be dried. Each of these cars is provided with raised walls 5 at its end and in the middle, the middle wall 5 constituting a partition, which divides the interior of said car into two 65 compartments, each compartment being used to contain a series of superposed drying boxes 7, which rest on ledges 6 of walls 5, being held so far apart as to leave space 70 for the circulation of air or other drying medium between them.

75 Each of these boxes may be constructed as shown in Fig. 4, having plates for its sides and bottom provided with numerous perforations 10; or, as shown in Fig. 5, a part of the box, preferably the bottom, may be made of rods and wire, permitting the ready passage of heat and air. This may consist, as shown, of two rows of rods 13 and 14 in different horizontal planes arranged alternately and fine wire 15 passing over them. In either case, the box is partly filled with comminuted absorptive material constituting a bed in which the articles or substances 8 to be dried may be conveniently embedded. Such material may be sand, salt, pulverized asbestos or any other material having the necessary characteristics. The substances 8 to be dried are entirely covered by this material and at no point touch the box or are exposed to the air. The bottom of the box 7, in the form illustrated by Fig. 4, is provided with external metal ribs 11 and internal metal ribs 12 to increase the surface

and conducting mass for receiving heat and transferring it to the substance 8 through the absorptive material 9.

When any substance or article 8 shrinks 5 in drying the enveloping substance 9 will similarly contract, keeping in contact or touch with the surface of said substance 8, so that the surface thereof will remain soft 10 since it receives from said material 9 sufficient absorbed moisture to counteract undue desiccation and hardening.

In preparing for the drying operation the boxes 7 are placed on the ledges 6 in the open sided cars 4, forming at least two vertical series of drying boxes for each car. The cars are then successively run on rails 3 into the receptacle casing 1 and the opening through which they enter the end of the same is closed by cover 2, as shown in Fig. 1.

20 For conveniently heating the receptacle and the drying boxes contained therein, steam may be admitted through pipes 25, Fig. 2, to heating pipes 23 arranged horizontally and longitudinally in vertical series between the sides of said receptacle and said cars. The drying may be effected in combination with this heat, by the admission and circulation of air, either under atmospheric pressure or under additional pressure; or by 30 the heat alone, a part of the steam generated thereby being drawn off continually and another part circulated through the boxes and contents so as to dry very gradually and evenly the entire mass of each article on 35 substance 8 treated.

In the former case, without mechanical air pressure, the air may be admitted in any convenient way and at any convenient point, but most conveniently by leaving off the cover 2. A vacuum pipe 22 leading from a compartment 18 in the bottom of the receptacle may then be utilized with any convenient means of suction to withdraw air and moisture from said receptacle and contents and cause the inflow of air which will then be caused to circulate within the receptacle 1 and through the boxes 7 by a pipe 17 leading from said compartment 18 to an end compartment 19 of said receptacle and a blower 16. The air pursues a zigzag course entering the rear pile or series of boxes at one side and passing from the other side thereof to the next pile or series and so on until it reaches the admission end of the receptacle and repeats its course through compartment 18 to pipe 17, continuing the circuit. Of course air and steam continually escape through pipe 22.

When the current of air is not used and steam generated within the receptacle is circulated through the boxes instead, the cover 2 is closed, as shown in Figs. 1 and 2, forming an end compartment 21, communicating with compartment 18 and forming part of

the circuit. Otherwise the action is the same, except that the current of steam through the boxes exercises no drying action, excepting such excess of moisture as it may carry away therefrom. But the pipe 22 continually abstracts moisture as well as air, the heat insures continued evaporation, the circulation of steam keeps the substances or articles 8 and the absorbent beds equally and moderately moist with a continual decrease of total moisture, so that the drying of substances treated is perfectly and evenly effected in every part. When the air is used in circulation the moisture of the beds and the articles within them must be relied on for like action without external air from any circulation of moisture.

Deflecting plates 20 (Figs. 1 and 2) are arranged on the inner face of the receptacle at both sides of the cars to insure the zigzag course of the air or steam above stated. 85
Horizontal, longitudinal, internal ledges (Fig. 2) of said receptacle combine with the bottoms of the cars to make a horizontal partition separating compartments 18 from the remainder of the interior of the receptacle except at the ends thereof. 90

Having thus described my invention, what I claim as new and desire to secure by Letters Patent is:

1. A bed of comminuted absorbent material in which articles of food may be embedded, in combination with a box containing the latter provided with numerous small openings in its sides and bottom and means for directing a drying current of aeriform fluid through said openings and said bed for the purpose set forth. 95 10

2. A superposed series of beds of absorbent material, arranged with intervals between them, in combination with a corresponding series of boxes, each having numerous small openings in its sides and bottom and means for directing a drying current of aeriform fluid through said openings and said beds in succession to properly dry articles of food embedded in said beds. 11

3. In combination with cars and drying boxes contained therein, both being adapted to allow flow of air or steam through said boxes and their contents, mechanical means for maintaining circulation of air or steam through the same, and a receptacle containing said cars and provided with ledges 26, which combine with the bottoms of said cars to form a lower compartment, the air or steam being directed through all the boxes and then returning through said lower compartment to said mechanical means of circulation.

4. In combination with a receptacle, a 1 series of absorbent beds arranged therein, mechanical means for producing a current through said beds of the greater part of the

steam produced by heating said receptacle and for maintaining this circulation without supply of steam from outside the casing, and means of escape for a part of this steam 5 in order that a continuous gradual drying of the entire substance of each article to be dried may be effected.

In testimony whereof, I have signed my name to this specification in the presence of two subscribing witnesses.

JØRGEN JØRGENSEN KRÜGER.
